UNITED STATES PATENT OFFICE

EDWARD L. McDEVITT, OF LOS ANGELES, CALIFORNIA, ASSIGNOR TO FRANK F. BARHAM,
OF LOS ANGELES, CALIFORNIA

PROTECTING MEANS FOR ROLLS OF PAPER

Application filed December 23, 1929. Serial No. 416,035.

My invention relates to protecting means for rolls of paper, and it has among its salient objects to provide a cheap and efficient cap which can be applied to the end of a roll of paper and secured thereto for the purpose of protecting the roll against damage, either from indentation or tearing or from water, said protecting means being made waterproof.

10 It is known that in handling and shipping large and heavy rolls of paper such as are used in newspaper publication, that the rolls are frequently damaged by being water-soaked at the end, or by reason of indentation or tearing the margin of the paper is so damaged that it is necessary to recut the roll and thus great waste and loss is entailed.

I have conceived the idea of making a special paper cap which can be applied to the 20 ends of a roll of paper in a pliable condition and clamped in place for a time to allow the same to set and become hard, after which the clamping means can be removed and the protecting means is thus secured in place and 25 becomes sufficiently hard and stiff as to form a most efficient protection for the end of the roll, as well as to protect it from being water-soaked.

I accomplish this by building up a body of 30 several layers of paper, secured together by means of a special matter which not only adheres the layers together, but is capable of hardening in an unusual manner and rendering the composite structure very stiff and 35 hard, much as starch hardens the bosom of a shirt or a collar.

In order to explain my invention I have 40 illustrated one practical embodiment thereof on the accompanying sheet of drawings, which I will now describe.

Figure 1 is a side elevation of the end of a 45 roll of paper, showing the wrapper or outside sheet torn away and indicating in light broken lines a protecting cap in place;

Figure 2 is an enlarged edge elevation of 50 five layers of paper as formed and prepared for application to the end of the roll;

Figure 3 is a side elevation of one form of 55 clamping means for pressing and temporarily

holding the structure over the end of the roll of paper;

Figure 4 is a flat view of the discs of paper which are laid together to form the cap, each successive sheet being torn away to expose 23 a portion of each sheet or disc and to show the portion covered by the adhesive used;

Figure 5 is an end view of the clamping means shown in Fig. 3;

Figure 6 is an elevation of the roll of paper 23 with the finished protecting means applied thereto; and

Figure 7 is an end view thereof.

Referring more in detail to the drawings, a roll of paper is designated 10, with a cover 23 or wrapper sheet 11, torn back in Fig. 1, and with an end plug 12, which projects slightly from the end of the roll and which also serves to make the roll easily tilted for the purpose of pushing the lifting lip of a lifting truck 23 under the end of the roll when it is desired to move it.

In Figs. 2 and 4, I have shown five sheets or 25 discs of heavy paper placed together flatwise and have designated these in Fig. 4, as 13, 14, 15, 16 and 17. I apply a wide ring of 30 special adhesive to each layer as it is applied for securing them together and to the top layer 17, is applied a similar or narrower ring of adhesive for causing the top disc or 35 layer to adhere to the wrapper sheet 11, around the outside of the roll as said composite structure is pressed over the end of the roll and clamped in place by a suitable clamping means.

In Figs. 3 and 5 I have shown a clamping 40 ring 18, of angle form in cross section, with extension fingers 19, and a wire ring securing the ends of said fingers together. Said wire ring is designated 20, and a tightening bolt 45 connection at 21, for drawing the ring 18 together after it has been pressed over the end of the roll with the layers making up the cap in place around the end of the roll, as will be readily understood. These layers 50 are applied while in their soft and pliable condition and are easily pressed over the end of the roll, and are then clamped and held 55 tight by the clamping means, as described and as will be clear from the showing. After 59

Figure 3 is a side elevation of one form of 60 clamping means for pressing and temporarily

the composite structure of the cap or protecting means has had time to set and to harden, the clamping means is removed, and the roll is ready for shipment and appears as seen in Fig. 6, with the balancing plug 12, bulging out sufficiently to serve its purpose and make it easy for the heavy roll to be tilted for the purpose described. The finished cap is designated 13', inasmuch as the bottom layer in Fig. 4, would become the outside layer in the applied cap.

I will now describe the special adhesive or stiffening and water-proofing matter I use in building up the composite structure forming the finished cap or protecting means. As I have actually used this preparation it is composed of the following ingredients: glue 23%; plaster of Paris 11%; cement 2%; paraffin 5%; marble dust 2% and water 57%.

This is prepared by mixing the glue and water and stirring the other ingredients thereinto with the result that it takes a gelatin form or consistency and when used as the adhesive for securing the layers of the paper together, it not only securely holds said layers together, but as it sets and hardens it forms said structure into a very hard protecting means for the roll of paper and is adhered to the outside wrapper of the roll and is thus easily removed when said outside wrapper is cut or torn intermediate the ends of the roll and removed therefrom. It also forms a water-proof structure for protecting the ends of said rolls.

I do not, of course, limit my invention to any particular or specific details herein described in order to set forth one practical embodiment thereof, realizing that many changes in said details can be made within the scope of my invention, and I intend that I shall only be limited by the hereto appended claims.

I claim:

1. A protecting wrapping for a roll of paper which includes a wrapper sheet around the roll of paper, a protecting cap formed of a plurality of superimposed layers secured together with an adhesive adapted to harden, with means for crimping the outer edge of said composite cap-forming layers over the end of said roll of paper and securing them around the end of said wrapper sheet and holding said formed cap until hard, said cap being removable with said wrapper sheet.

2. A protecting wrapping for a roll of paper having an end plug in each end projecting slightly beyond the end of said roll of paper, said protecting wrapping including a wrapper sheet around the roll of paper as a separate wrapper, a protecting cap formed of a plurality of superimposed layers secured together flatwise by means of adhesive adapted to harden and applied in rings around the outer edges of said layers, whereby the central part of said layers is free of adhesive

in its inner side over the end of said plug, and means for crimping the outer edge of said composite cap-forming layers over the end of said roll of paper and securing them around and to the end of said wrapper sheet and holding them until hard, said wrapper sheet holding said cap on said roll of paper and releasing said cap when said wrapper sheet is removed, said plug bulging said cap in the center for tilting purposes, substantially as shown and described.

Signed at Los Angeles, Los Angeles County, California, this 9th day of December, 1929.
